UNITED STATES PATENT OFFICE.

STANLEY H. PAGE, OF SAN FRANCISCO, CALIFORNIA, ASSIGNOR TO UNION GAS ENGINE COMPANY, OF OAKLAND, CALIFORNIA, A CORPORATION OF CALIFORNIA.

ENGINE-CYLINDER AND JACKET.

1,228,815.

Specification of Letters Patent. Patented June 5, 1917.

Application filed December 11, 1916. Serial No. 136,156.

To all whom it may concern:

Be it known that I, STANLEY H. PAGE, a citizen of the United States, residing at the city and county of San Francisco and 5 State of California, have invented certain new and useful Improvements in Engine-Cylinders and Jackets, of which the following is a specification.

This invention relates to internal combustion engines and more particularly to the cylinder construction thereof wherein there are employed cylinders having separate jackets, preferably of light weight material, and the invention has for its principal objects to provide a simple, efficient and cheaply constructed means for detachably securing the jacket in position on the cylinder and whereby a water tight joint is provided surrounding the securing means 20 and enabling the cylinder and head to be formed of a single casting and enveloped by a suitable sheet metal jacket preferably of light weight material. This construction reducing the cost of manufacture of the 25 cylinder and jacket and permits the heat of the cooling fluid to more quickly radiate through the thin jacket than if the same is formed of heavy casting. This construction also reduces the weight of the cylinders 30 over that type wherein the cylinder and jacket are formed in a single casting.

With the above mentioned and other objects in view the invention consists in the novel construction and combination of parts, 35 hereinafter described, illustrated in the accompanying drawing and pointed out in the claims hereto appended; it being understood that various changes in the form, proportion, size, and minor details of construction 40 within the scope of the claims may be resorted to without departing from the spirit or sacrificing any of the advantages of the invention.

To more fully comprehend the invention, 45 attention is directed to the accompanying drawing wherein,

The figure is a broken side elevation, partly in section of the preferred embodiment of my invention, illustrating the cylinder, the removable jacket and my improved jacket attaching means.

Referring more particularly to the drawings, 1 indicates a suitable engine cylinder, preferably in the form of a casting, and for 50 the purposes of illustration a cylinder of

the commonly termed, over-head valve type is employed. The cylinder is provided with the usual combustion chamber, side and head walls 2 and 3 and the usual intake and exhaust channels 4, only one of which is illustrated, and it opening as at 5 into the combustion chamber, and as at 6 to the exterior of the cylinder. Into said open end 6, is adapted to be secured, in any suitable manner, as by threaded attachment, a suitable 60 inlet or exhaust manifold (not shown) dependent of course upon whether the channel is employed for inlet or exhaust purposes.

The opening 5, between the cylinder combustion chamber and the channel 4, is controlled by the usual puppet valve (not shown), the stem of which extends upwardly through an outwardly inclined tubular guide 7, which projects through the interior wall 70 8 of the channel 4. The material surrounding the upper end of the guide 7 projects upwardly above the top of the flange 9 surrounding the opening 5 of the channel 4 and provides a circular boss or lug 10, having 80 vertical side walls which are preferably threaded as at 11, and which extend in a plane perpendicular to the upper horizontal surface of the flange 9 and through said lug or boss the guide 7 passes at an angle. 85

A water jacket 12, preferably of sheet metal is removably positioned over the cylinder, to provide a cooling chamber 13 surrounding the same, and said chamber is provided in its head wall 14, with one or more 90 openings 14' through each of which, one of said threaded bosses or lugs 10 is adapted to project when the jacket is positioned on the cylinder as in the drawing. The jacket 12 is removably held in position on the cylinder 95 by suitable securing means 15, preferably in the form of washers or nuts having threaded engagement with the boss 10. The clamping of the jacket head on to the flange surrounding the bosses provides a water 100 tight joint at this point and if desirable, suitable packing may be interposed, between the jacket head and flange or between the securing means and jacket head.

By providing a circular boss or lug 10 105 having its side walls extending in a plane perpendicular to the flange 9 and through which the valve guide extends at an angle, I am enabled to employ a jacket member, circular in form and having a flat, preferably 110

2
circular top or head, which rests on the upper wall surface of the flange 9 surrounding the base in the lug or boss; whereas, if the sides of the lug are parallel with the axis 5 of the valve guide, the flange 9 is required to be beveled or inclined to lie at right angles thereto and a portion of the head of the jacket is also required to be inclined to enable the conventional form of nut or washer 10 to be employed.

Having thus described my invention, what I claim is:

1. In combination with a cylinder for internal combustion engines of the overhead valve type, provided with upwardly extending tubular guides in the head thereof for receiving the stems of the cylinder controlling valves, the upper ends of said guides providing bosses projecting upwardly from 15 said cylinder, a flange surrounding the base of each boss the outer surface of said bosses disposed perpendicularly to the said flange and said guides passing through the bosses at an angle, a jacket for positioning over 20 and surrounding the cylinder side walls in spaced relation thereto and provided with openings in its head and through each of which one of said bosses projects, and means 25 for positioning over said bosses and engaging 30 the jacket head for removably securing said jacket in position on the cylinder with the head thereof in contact with said flange.
2. In combination with a cylinder for internal combustion engines of the overhead valve type provided on its head with one or 35 more tubular, externally threaded bosses extending vertically from the cylinder head and each providing a valve guide the bore of which is disposed at an angle and the ex-

terior wall perpendicular to the top surface 40 of the cylinder, a jacket for removably positioning over and surrounding the cylinder side walls in spaced relation thereto and provided on its head with one or more openings through each of which one of said 45 bosses extends, and a nut for threaded engagement with each of said bosses for contacting with said jacket head for detachably securing the jacket in position on the cylinder. 50

3. In combination with a cylinder for internal combustion engines of the overhead valve type, provided with upwardly projecting guides through which the stems of the controlling valves extend the bores of said 55 guides being disposed at an angle to each other and the outer surfaces thereof arranged perpendicular to the top wall of the cylinder in parallel spaced relation, the upper ends of said guides providing shouldered 60 bosses, a headed jacket member for positioning over and surrounding the cylinder side walls in spaced relation thereto and provided in its head with openings through each of which one of said bosses extends, a 65 nut for threaded attachment with said bosses for forcing said jacket head into contact with the shoulder surrounding said bosses for detachably securing the jacket in position on the cylinder. 70

In testimony whereof I have signed my name to this specification in the presence of two subscribing witnesses.

STANLEY H. PAGE.
